(57) **CLAIM**

The ornamental design for a furniture foot, as shown and described.

DESCRIPTION

FIG. 1 is a lower perspective view of a furniture foot showing our new design;

FIG. 2 is another lower perspective view thereof;

FIG. 3 is a front elevation view thereof;

FIG. 4 is a right side elevation view thereof, the left side being a mirror image; and,

FIG. 5 is a bottom plan view thereof.

The broken lines show environmental subject matter and form no part of the claimed design. The embodiment is shown with symbolic breaks in length. The appearance of any portions of the design between the break lines form no part of the claimed design.
